CLAIM

The ornamental design for two-hole deck-mount faucet, as shown and described.

DESCRIPTION

FIG. 1 is a perspective view of the two-hole deck-mount faucet according to the invention, the deck and display indicia that do not form part of the invention being shown in dashed lines;

FIG. 2 is a left-side elevation view of the faucet;

FIG. 3 is a right-side elevation view of the faucet;

FIG. 4 is a front elevation view of the faucet;

FIG. 5 is a back elevation view of the faucet; and,

FIG. 6 is a top view of the faucet.
